SYNCHROTESTER CASE FOR PHOTOGRAPHIC EQUIPMENT OR THE LIKE

Ralph T. Gardner, Denver, Colo.

Application November 16, 1953, Serial No. 27,619

Term of patent 3½ years

(Cl. D61—1)

FIG. 1

FIG. 2

FIG. 3

Figure 1 is an isometric view of a synchrotester case for photographic equipment or the like with the cover and screen closed, showing my new design.

Figure 2 is a side elevational view thereof with the cover and screen in one position of use; and

Figure 3 is an end elevational view thereof as shown in Figure 2.

I claim:

The ornamental design for a synchrotester case for photographic equipment or the like, as shown.
